UNITED STATES PATENT OFFICE.

FREDERICK W. HUESTIS, OF BOSTON, MASSACHUSETTS, ASSIGNOR TO THE UNIVERSAL SAFETY-TREAD COMPANY, OF JERSEY CITY, NEW JERSEY, A CORPORATION OF NEW JERSEY.

STAIR-TREAD, &c.

SPECIFICATION forming part of Letters Patent No. 743,164, dated November 3, 1903.

Application filed September 1, 1899. Serial No. 729,220. (No model.)

To all whom it may concern:

Be it known that I, FREDERICK W. HUESTIS, a citizen of the United States, residing at Boston, in the county of Suffolk and State of Massachusetts, have invented certain new and useful Improvements in Stair-Treads and the Like, of which the following is a specification, reference being had therein to the accompanying drawings.

10 Figure 1 is a top plan view, Fig. 2 an edge view, and Fig. 3 a cross-sectional view, on line 3 of Fig. 1 of my improved tread. Fig. 4 is a top plan view, Fig. 5 an edge view, and Fig. 6 a cross-sectional view, on line 6 of Fig. 4 of a modified form of my new tread. Figs. 7 to 12, inclusive, illustrate other modifications.

15 The object of my invention is to provide non-slipping stair-treads, sidewalk-lights, coal-hole covers, wagon, carriage, and car steps, door-mats, and mats for decks of steamers and men-of-war, and any and all other uses to which non-slipping treads may be put, my new treads comprising in their 20 construction a hard durable metal of any kind combined with non-slipping material of any kind and being preferably made of steel and lead.

25 In the drawings illustrating the principle 30 of my invention and the best mode now known to me of applying that principle, α is a rod or wire of hard metal, preferably steel, bent upon or in relation to itself in any suitable manner, so as to form spaces α' between opposed portions of the tire, some or all of these 35 spaces being filled in any suitable manner with non-slipping material b —such as lead, for example. Inasmuch as the opposed walls of the spaces α' curve away from each other, 40 so forming overhangs at α^2 below (as well as above) the middle of the wires or rods, cross-sectionally considered the lead b in each space α is anchored on the under side of the tread by the overhangs at α^2 of the side walls of 45 the spaces which receive the non-slipping material. It will be observed that a tread made in this way is reversible—that is, it may be

used either side up. The end portions α^3 of the rod or wire α are preferably bent angularly past the ends of the reversely-bent body-forming portion of the wire and brazed at their extremities or otherwise secured firmly in place, so as to hold the tread in shape. If desired, one or more base-supports α^4 may be used to keep the body-forming portion of the 55 rod or wire in proper relation one portion to another, these supports not only supporting the flat surfaces of the tread when it is in use, but also binding the tread edgewise, so as to prevent lateral displacement of the hard 60 and non-slipping material.

It will be readily understood that the rod or wire may be bent into any desired form, either rectangular, as shown, or polygonal, or be coiled, so as to form a circular tread, all without departure from my invention.

65 Treads embodying my present invention are very economically made and are readily formed into a great variety of shapes to meet either general or special requirements as to 70 configuration. Preferably the wire or rod is continuous.

In Figs. 4, 5, and 6, illustrating a modification, a metal tape d , preferably of steel, is substituted for the rod or wire, the opposite 75 edges of the bent tape between the wear-surfaces of the tread and the spaces between the bent tape or strip being filled in whole or in part with lead or other non-slipping material. In some instances the lead will be held sufficiently fast in place for some uses without any treatment of the tapes; but in practice I prefer to form opposed portions of the tape—that is to say, the side walls of the lead-receiving spaces—with recesses, as at d' , through 80 which the lead may pass, so as to become securely anchored in the metal portion of the tread, or being formed with a lengthwise depression d^2 on its flat side, as in Figs. 7 and 8, in which the non-slipping material is anchored when the tape is bent so as to bring 85 portions of it in opposition to other portions.

In Fig. 9 I show a cross-sectional view of another modification in which the base-sup-

port f is dish-shaped, the combined hard and non-slipping tread being mounted in said dish-shaped support.

In Fig. 10 I show another modification in which the hard-metal portions are a series of separate strips g , mounted at their ends in the transverse supports g' .

In Fig. 11 I show another modification in which the hard metal is a continuous strip h , crimped and mounted on the base-support h' , with the bends h^3 lying in the opposite flat sides of the tread, the lead h^3 filling the spaces between opposed portions of the hard-metal strip.

In Fig. 12 I show another modification in which a hard-metal tape is crimped and set edgewise, with spaces j' between its opposed

sides, non-slipping material j^2 being filled in and the whole supported by a suitable base-support j^3 .

20

What I claim is—

A reversible tread-surface for stairs, side-walks and similar places, consisting of a core of wear-resisting material, and a body of softer material, in which said core is embedded, and projects from both surfaces thereof, forming both surfaces of the tread substantially alike and uniform, for the purpose set forth.

In testimony whereof I affix my signature in presence of two witnesses.

FREDERICK W. HUESTIS.
